(57) **CLAIM**

The ornamental design for a desk, as shown and described.

DESCRIPTION

FIG. 1 is a perspective view of a desk in an extended position, showing my new design.

FIG. 2 is a front elevation view thereof.

FIG. 3 is a rear elevation view thereof.

FIG. 4 is a right side elevation view thereof. A left side elevation view is a mirror image of the right side elevation view.

FIG. 5 is a top plan view thereof.

FIG. 6 is a bottom plan view thereof.

FIG. 7 is a cross sectional view taken along line 7-7 in FIG. 2.

FIG. 8 is a cross sectional view taken along line 8-8 in FIG. 2, which omits internal structure; and,

FIG. 9 is a perspective view of a desk shown in a collapsed position.

All broken line portions of the figure drawings is included to show portions of the article that form no part of the claimed design.
